(57) **CLAIM**

The ornamental design for a handheld air compressor, as shown and described.

DESCRIPTION

FIG. 1 is a perspective view of a handheld air compressor; FIG. 2 is a left side view of the handheld air compressor of FIG. 1;

FIG. 3 is a right side view of the handheld air compressor of FIG. 1;

FIG. 4 is a front view of the handheld air compressor of FIG. 1;

FIG. 5 is a back view of the handheld air compressor of FIG. 1;

FIG. 6 is a top view of the handheld air compressor of FIG. 1; and,

FIG. 7 is a bottom view of the handheld air compressor of FIG. 1.

The broken lines shown in the drawings are included for the purpose of illustrating an environmental structure and form no part of the claimed design.
